UNITED STATES PATENT OFFICE.

JAMES A. WHEELER, OF BOONE, IOWA.

LUBRICATOR FOR HOT BOXES OF RAILWAY-CAR JOURNALS.

SPECIFICATION forming part of Letters Patent No. 625,002, dated May 16, 1899.

Application filed December 27, 1898. Serial No. 700,483. (No model.)

To all whom it may concern:

Be it known that I, JAMES A. WHEELER, a citizen of the United States, residing at Boone, in the county of Boone and State of Iowa, have 5 invented a new and useful Lubricator for Hot Boxes of Railway-Car Journals, of which the following is a specification.

The object of this invention is to provide a device of simple, strong, durable, and inexpensive construction in the nature of an attachment that may be readily, quickly, and easily applied to the journal-box-supporting frame of a railway-car to constantly feed lubricating-oil to the journal and in such a quantity as to prevent the journal from running dry and to thereby gradually cool the journal.

My invention consists in the construction, arrangement, and combination with the oil-tank of an adjustable and reversible clamp 20 that may be attached to either side of the said frame to support the oil-tank in proper position adjacent to the box; and my invention consists, further, in the construction of the pipe for conveying the oil from the tank 25 to the journal, so that the oil may be fed to any desired spot upon the journal irrespective of the position of the oil-tank upon the frame, and in certain other details of construction, arrangement, and combination of parts, 30 as hereinafter more fully set forth, pointed out in my claims, and illustrated in the accompanying drawings, in which—

Figure 1 shows a side elevation of a part of the journal-box-supporting frame of a freight-car and the wheel in position relative thereto and also my improvement applied as in practical use. Fig. 2 shows an end elevation of the same, with dotted lines to indicate the position of the oil-feeding pipe relative to the 35 journal. Fig. 3 shows a similar view of the corresponding portions of a passenger-coach with my device applied thereto. Fig. 4 shows a vertical sectional view of the oil-tank. Fig. 40 5 shows in perspective the perforated end of the oil-feeding pipe. Fig. 6 shows a perspective view of the clamp for securing the oil-tank to the journal-box-supporting frame.

Referring to the accompanying drawings, I have used the reference-numeral 10 to indicate the journal-box-supporting frame of the kind ordinarily used on freight-cars. At its 45 end is the journal-box 11, also of the usual

construction, having a hinged cover 12. The car-wheel is indicated by the numeral 13, and its journal by the numeral 14. The brasses 55 within the box and in which the journal runs are not shown. However, all of said parts are of usual construction.

My attachment comprises a two-part clamp composed of two pieces of metal 15 and 16, 60 having a hinge 17 therein and designed to encircle a part of the frame 10. The ends of the clamp opposite the hinge are normally separated a slight distance when passed around the part of the frame 10, and a thumb-screw 18 is passed through one part and seated in the opposite part. Obviously when the clamp is passed around the frame 10 the thumb-screw may be made to enter the screw-threaded portion of the clamp, and as the ends are 65 drawn together by the screw the clamp will be firmly secured in position upon the frame, and obviously the clamp will adapt itself to slight variations in the size of the frame parts. One end of the clamp is extended outwardly 70 a considerable distance and twisted to a position almost at right angles to the body portion of the said part, and an opening 19 is made therein.

The reference-numeral 20 indicates a tank 80 for containing lubricating-oil, and 21 indicates a metal band passed around the central portion in this tank and riveted thereto. Its ends are bent outwardly from the tank 85 parallel with each other and an opening made in each end, one of which openings is screw-threaded. A thumb-screw 22 is provided and arranged to pass through the openings in the band 21 and also through the opening 19, and obviously this screw will serve to 90 clamp the parts together, and, further, the tank may be tilted in a vertical plane to desirable position.

Reference-numeral 23 indicates a valve-seat in the bottom of the tank, and 24 a plunger-rod seated in the top of the tank and provided with a disk at its top, whereby the plunger-rod may be turned. At its lower end is a valve 26 to engage the seat 23, and from this seat a pipe 27 projects first downwardly, 95 then horizontally at 28, and then horizontally at right angles at 29. In its end a number of holes 30 are made to permit the free passage of oil therefrom. A feed-opening 31 is 100

made in the top of the tank and a cone-shaped screw-cap 32, having an air-vent 33, seated in said opening.

In the modification shown in Fig. 3 the only 5 difference over the construction shown in Fig. 2 is that the under portion of the clamp is made larger, so that it will encircle the wooden frame 37 usually found in passenger-coaches.

In practical operation when the operators 10 of a train discover that one of the boxes has become hot, which may be easily seen by smoke issuing therefrom, the train is stopped and one of the oil-tanks is clamped to the frame adjacent to the box thus affected. The 15 position of the tank with relation to the box may be adjusted by changing the position of the clamp upon the frame so that the pipe will stand in the box at the side of the journal, and, furthermore, the position of the pipe 20 with relation to the box may be adjusted vertically by tilting the tank up or down, which may be accomplished by a manipulation of the thumb-screw 22. By this means it is obvious that the perforated end 30 of the oil- 25 feeding pipe may be placed in position adjacent to the journal. When this has been done and all of the parts made fast, the disk 25 is operated and the valve 26 raised, thus permitting a flow of oil through the feed-pipe 30 and to the journal. Then the car may be at once started without repacking the box and obviously the journal cannot go dry, and hence after a few miles run, or before the supply of oil in the tank 20 is exhausted, the box 35 will have again become cooled and a sufficient supply of oil in the box is all that is necessary. It is obvious, further, that by reason of the peculiar construction of the clamp the same clamp may be used for either 40 side of the frame 10, and it will support the

tank in a substantially vertical position when on either side. The placing of a number of holes in the end of the feed-pipe will prevent any possibility of the flow of oil being stopped when the end of the pipe is clogged with 45 waste or the like.

Having thus described my invention, what I claim, and desire to secure by Letters Patent of the United States, is—

1. A device for lubricating the journal- 50 boxes of railway-cars comprising a clamp designed for detachable connection with the car-truck near the journal-box, an oil-tank, a pipe projected downwardly therefrom and then horizontally, means for securing the 55 clamp to the tank, and for tilting the tank relative to the clamp so that the lower end of the pipe may be positioned to lie adjacent to the journal in the boxes, for the purposes stated.

2. A lubricator attachment for railway-cars, comprising, a clamp of two parts hinged together and capable of encircling a part of the truck-frame, a thumb-screw for drawing the free ends of said parts together, an oil- 65 tank, a metal pipe leading downwardly and then horizontally from the tank, means for regulating the flow through the pipe, and means for pivotally connecting the said metal band to the said clamp and for securing the 70 said pivoted parts in the desired position whereby the tank may be so positioned as to hold the pipe in proper position within the journal-box, substantially as and for the purposes stated.

JAMES A. WHEELER.
